MULTI-DIRECTIONAL SPEAKER

Wilfried Schneider, 59 Perivale Crescent,
Scarborough, Ontario, Canada

Filed Dec. 23, 1971, Ser. No. 211,851

Term of patent 7 years

Int. Cl. D14—01

U.S. Cl. D26—14 G

FIG. 1

FIG. 2

FIG. 1 is a perspective view taken from the top of a multi-directional speaker embodying my new design;

FIG. 2 is a perspective view from the bottom of the same side thereof.

I claim:

The ornamental design for a multi-directional speaker, as shown and described.
